(57) **CLAIM**

The ornamental design for a shelf for refrigerator as shown and described.

DESCRIPTION

FIG. 1 is a front perspective view of a shelf for refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area ‘8’ as identified in FIG. 1; and,

FIG. 9 is a front perspective view of the shelf for refrigerator shown in an alternate configuration of use where the front shelf is slid backward.

The evenly spaced broken lines depict portions of the shelf for refrigerator that form no part of the claimed design. The unevenly spaced broken lines are for the purpose of annotating the enlarged views only and form no part of the claimed design.
